(57) **CLAIM**

The ornamental design for a combined monitor screen, video tape recorder and video camera, as shown and described.

DESCRIPTION

FIG. 1 is a top, front and right side perspective view of a combined monitor screen, video tape recorder and video camera according to our design;

FIG. 2 is a rear elevational view thereof;

FIG. 3 is a front elevational view thereof;

FIG. 4 is a bottom plan view thereof;

FIG. 5 is a top plan view thereof;

FIG. 6 is a left side elevational view thereof;

FIG. 7 is a right side elevational view thereof;

FIG. 8 is a top, front and left side perspective view thereof with the monitor screen swung 90° relative to the grip and rotated 90° relative to the lens;

FIG. 9 is a top, rear and right side perspective view thereof with the monitor screen swung 90° relative to the grip and rotated 90° relative to the lens; and,

FIG. 10 is a top, rear and left side perspective view thereof with the monitor screen swung 270° relative to the grip and rotated 90° relative to the lens.

Applicants hereby disclaim the written material shown in the drawings figures as such written material forms no part of the present design.
